The ornamental design for a kisser for archery bow, as shown and described.

DESCRIPTION

FIG. 1 is a top and front perspective view of a kisser for archery use, showing my new design;

FIG. 2 is an enlarged top plan view thereof;

FIG. 3 is a bottom plan view thereof;

FIG. 4 is a side elevational view thereof as seen from the front of an orientation corresponding to FIG. 2;

FIG. 5 is a side elevational view thereof as seen from the side of an orientation corresponding to FIG. 2;

FIG. 6 is a side elevational view thereof as seen from the rear of an orientation corresponding to FIG. 2; and,

FIG. 7 is a top perspective view of a second embodiment, all parts are identical to the first embodiment, except for a vertical slot.
